UNITED STATES PATENT OFFICE.

CLARENCE E. ELLIOTT AND ORVILLE L. NICHOLS, OF KANSAS CITY, MISSOURI.

DESIGN FOR A RADIATOR ORNAMENT.

59,725.

Specification for Design.

Patented Nov. 22, 1921.

Application filed July 20, 1921. Serial No. 486,272. Term of patent 7 years.

To all whom it may concern:

Be it known that we, CLARENCE E. ELLIOTT and ORVILLE L. NICHOLS, citizens of the United States, residing at Kansas City, in the county of Jackson and State of Missouri, have invented a new, original, and ornamental Design for a Radiator Ornament, of which the following is a specification, reference being had to the accompanying drawing, forming part thereof.

Figure 1 is a rear perspective view of the design.

Fig. 2 is a front, elevation view of the design, and

Fig. 3 is an end view of the same.

We claim:

The ornamental design for a radiator ornament, as shown.

CLARENCE E. ELLIOTT.
ORVILLE L. NICHOLS.
